UNITED STATES PATENT OFFICE.

LOUIS ROCKELMAN, OF SALT LAKE CITY, UTAH.

BOILER-PIPE CLEANER.

Application filed December 21, 1926. Serial No. 156,209.

My invention relates to cleaning pipes and has for its object to provide a new and efficient apparatus for cleaning the water pipes in a steam heating furnace.

5 A further object is to provide a new and efficient apparatus for cleaning the scale out of water pipes which are subjected to heat in a furnace.

10 A still further object is to provide a new and economical apparatus for cleaning water pipes in a boiler, which have become stopped up with scale from the lime in the water depositing on the inner faces of the pipes, and which will clean pipes that are not on the 15 same angle as the plug opening in the front of the heater.

20 These objects I accomplish with the device illustrated in the accompanying drawings in which similar numerals and letters of reference indicate like parts throughout the several views and as described in the specification forming a part of this application and pointed out in the appended claims.

25 In the drawings in which I have shown the best and most preferred manner of building my invention Figure 1 is a section of a portion of a water heating furnace showing one pipe sectioned with my cleaner in place therein. Figure 2 is a side elevation of the 30 cleaning apparatus. Figure 3 is an end view of the screw collar. Figure 4 is a side elevation of the inner collar in which the cleaning screw operates.

35 In the drawings I have shown the fire grate composed of parallel pipes as A the header pipe as B and the front of the boiler as C. In most boilers the pipes which carry the water are on a sloping plane as shown in Figure 1 and the front of the furnace or boiler 40 is perpendicular so that an object being placed through the front of the boiler would have to be at an angle to the front in order to follow the direction of the pipes A. In the front side of the said boiler there are plugs screwed 45 into cleaning holes 1 which normally hold the water within the boiler and pipes. My apparatus is to be placed through the said holes 1 and an externally threaded collar 2 is screwed into the hole 1 to firmly hold the apparatus in place while cleaning the pipes. 50 Near one end of the said collar 2 I provide set screws 3, 4 and 5, which set screws are to hold an internally threaded flanged member 6 therein which member 6 has a flange 7 on one end and the central portion of the mem-

ber 6 adjacent to said collar is partially cut spherical as at 7^a to enable the operator of the apparatus to tilt the central portion of the tool upwardly or downwardly as necessary and still remain within the outer collar 80 2. The said collar 6 is internally bored and threaded to receive a threaded rod 8. Near one end of the said rod 8 a cross hole 9 is bored to receive a cutting tool 10. The end of the said rod 8 is bored and internally 65 threaded to receive a set screw 11 which screw 11 normally holds the cutting tool 10 in place in fixed relation to the rod 8 but the tool may be moved as necessary to lengthen or shorten the cut by loosening the said set screw 11. 70 The other end of the said rod 8 is enlarged as at 12 and the extreme end is formed into a hexagonal shape nut 13 to afford a hold for a wrench to turn it by. Near the end nut 13 a hole 14 is bored through which a bar 15 75 may be passed by which the rod may be turned when boring out the inside of a pipe. The angle at which the tool works is determined by setting the screws 3, 4 and 5.

80 The operation of my apparatus is as follows. To clean out the pipes of a furnace or boiler the water is drained therefrom and the front plugs are removed from the holes 1. The collar 2 is then screwed therein and the rod 8 tilted until it is on the angle of the 85 pipes A of the boiler. The set screws 3, 4 and 5 are then set on the member 6 and the apparatus is ready to begin the cutting out of the scale from within the pipes A. The rod 8 is advanced until the cutting tool 10 is starting into the end of the pipe A and the amount of cut necessary to clean the pipe is then determined. The tool 10 is adjusted to the correct amount of cut, and the rod 11 turned and the tool 10 held rigid in the rod 8. The handle 90 15 is then inserted through the hole 14 and the rod 8 turned. As the threads in the collar force the rod 8 along, the cutting tool 10 will cut all scale from the interior of the pipe A and when the length of the pipe has been covered the scale is all free and may be washed out with a little water and the pipe 95 A will then be clean. Each pipe in a boiler may be cleaned the same way and much time and labor saved through the use of my invention.

100 Should there be a leak in one of the tubes of a boiler it would not be necessary to clean the whole pipe to fix it but the end near the front might be cleaned by my apparatus and 105 110

the pipe then tightened, thereby saving much time.

It will be obvious that slight modifications may be made in the apparatus without departing from the scope of the claims.

Having thus described my invention I desire to secure by Letters Patent and claim:—

1. In an apparatus of the class described the combination of an externally threaded collar; set screws through one end of said collar; an internally threaded member to fit within said collar, and having a flange on one end and the portion of the member near said flange slightly spherical in form to allow for 10 tilting movement of the member within said collar; a threaded rod to operate in the threads in said flanged member; a cutting blade adjustably secured near the end of said rod; a set screw to hold said cutting blade: a 15 hole through the other end of said rod; and a

handle passed through said hole to turn said rod.

2. In a pipe cleaner for boilers the combination of an externally threaded collar adapted to fit in the front cleaning hole of a 25 boiler; a flanged member loosely fitting within said collar and held therein by set screws through said collar and to be tilted at an angle therein to fit the angle of the pipe being cleaned by adjustment of the set screws; a threaded rod through said flanged member adapted to be advanced and retarded through said collar by the threads thereon and therein; and an adjustable cutting blade in the end 30 of said rod to cut the scale from the interior 35 of the boiler pipes.

In testimony whereof I have affixed my signature.

LOUIS ROCKELMAN.
